UNITED STATES PATENT OFFICE

CHARLES K. HOLT AND JOHN B. MERRITT, OF SANTA BARBARA, CALIFORNIA

DRILL BIT

Application filed April 8, 1930. Serial No. 442,667.

This invention relates to a well bit for use in the rotary method of well drilling, and has for one of its objects to provide a bit of this character which is adapted for use in various kinds of earth formations, and which is operable to penetrate the earth formation as the result of a true cutting action as distinguished from a scraping action.

Another object of the invention is to provide a drill bit of the character stated which is self-sharpening and which is adapted to handle the circulating fluid in a manner to maintain its cutting parts free of the cuttings. 10 The invention has for a further object to provide a drill bit of the character stated which does not wobble or have undesirable motion in the hole being drilled, and which is adapted to drill a straight hole of uniform gauge. 20

With the foregoing and other objects in view, the nature of which will appear as the description proceeds, the invention consists in the construction, combination and arrangement of parts hereinafter fully described and claimed, and illustrated in the accompanying drawings, wherein:

Fig. 1 is a view in side elevation of a drill bit constructed in accordance with our invention. Fig. 2 is a bottom plan view of the drill bit. Fig. 3 is a view partly in vertical section and partly in side elevation of the drill bit. Fig. 4 is a sectional view taken on the vertical plane indicated by the line 4-4 of Fig. 2. Fig. 5 is a sectional view taken on the vertical plane indicated by the line 5-5 of Fig. 2.

The bit provided by the present invention includes a shank 1 and a cutter head 2 on the lower end of the shank. The shank 1 is provided at its upper end with an externally screw-threaded pin 3 to facilitate its connection with a drill collar, or the like, on the lower end of a drill stem or drill pipe. 40 The head 2 is provided with arms 4 which extend radially outward therefrom and are equally spaced, and it is provided with a plurality of like series of cutters 5, 6 and 7.

The cutters 5, 6 and 7 of each series are 50 aligned and extend substantially radially

outward from the axial center of the head 2. The cutters 5 which are the outer cutters are provided at the outer ends of the arms 4, and extend from the upper ends of the arms to points below the arms. The 55 cutters 5 are of arcuate formation in horizontal cross section, and have their convex sides arranged forwardly, or in the direction of the rotation of the bit, to provide outer vertical cutting edges 8. The cutters 60 5 are reinforced at their rear sides with central longitudinal ribs 9 and are provided at their lower ends with cutting edges inclined or curved upwardly and inwardly. The inner cutters 7 and the intermediate 65 cutters 6 are similar in shape, and the former extend downwardly from the lower end of the head 2, and the latter project downwardly from the lower sides of the arms 4. The cutters 6 and 7 are of hollow triangular formation or of V shape in cross section and are arranged with their open sides rearwardly disposed to have vertical forward cutting edges 10. The cutters 6 and 7 have their lower ends 11 inclined upwardly and rearwardly. The cutters 5, 6 and 7 of each series are equally spaced, and the inner cutters 7 of the respective series are equally spaced about the longitudinal center of the head 2. 70 75

Like cutters 12 project downwardly from the lower end of the head 2 between the inner cutters 7 and are arranged at opposite sides of the axial center of the head. The cutters 12 may be spiralled and may 80 be comparatively short. The cutters 7 extend below the cutters 12, the cutters 6 extend below the cutters 7, and the cutters 5 extend below the cutters 6. In other words, the cutters 12, 7, 6 and 5 have their lower 85 ends stepped downwardly and outwardly from the vertical axis of the bit.

The shank 1 is provided with a longitudinal fluid passage 13 which communicates at its lower end with branch ports 14. 90 The ports 14 pass through the head to discharge from its lower end at points forwardly of and adjacent the inner cutters 7. The passage 13 also communicates with a port 15 discharging downwardly between 95 100

the cutters 12. The passage 13 is provided to pass the circulating fluid which is forced down the drill string to discharge from the ports 14 and 15 in advance of and close to the several cutters.

Due to their formation, the cutters have a cutting instead of a scraping action, and will pass downwardly through hard earth formation with the use of comparatively little force. Due to the transverse V shaped formation of the cutters 6 and 7, the rear portions of their sides will wear away faster than the front portions thereof with the result that the cutters will remain sharpened until completely worn away. As the cutters of each series thereof are relatively spaced, and due to the manner in which the circulating fluid is delivered to the hole with respect to the cutters, the cutters are effectively washed and kept free of cutters. Furthermore, the spacing of the cutters of the respective series permits them to pass through loose earth formations without becoming clogged.

25 The downward and outward inclination of the cutters causes the bit to cut in a coring manner, with the result that a straight hole of even gauge will be drilled. All parts of the tool may be cast integral, and 30 the active edges of the cutters may be hardened or provided with hard cutting material.

While we have described the principle of the invention, together with a typical embodiment thereof, it is to be understood that the structure shown is merely illustrative and that various changes may be made when desired, as fall within the scope of the invention as claimed.

40 We claim:

1. A drill bit having a plurality of series of downwardly extending cutters, the cutters of each series being relatively spaced and extending outwardly from the axial center of the bit, the outer cutter of each series being of arcuate form in cross section with its concave side arranged forwardly, the inner and intermediate cutters of each series being of hollow triangular formation 45 with their open sides disposed rearwardly, the cutters of each series increasing in length outwardly, said triangular cutters having upwardly and rearwardly inclined lower ends, and other cutters arranged between and shorter than the inner cutters and the bit being provided with a circulating fluid passage discharging at points in advance of the cutters.

2. A well bit of the character described including, a head, spaced radially projecting arms on the head, and a plurality of series of downwardly projecting cutters, each series including an outer cutter of arcuate cross section at the outer end of an 55 arm, an intermediate cutter of V-shaped

transverse cross section on the arm, and an inner cutter of V-shaped transverse cross section on the lower end of the head, the intermediate and the inner cutters having their open sides facing rearwardly whereby they remain sharpened during use, the lower ends of the cutters being stepped downwardly and outwardly relative to the longitudinal center of the head.

70 In testimony whereof we hereunto affix 75 our signatures.

CHARLES K. HOLT.
JOHN B. MERRITT.
